SAFETY DISK WHEEL

Louis Verderosa, Ozone Park, N. Y.

Application April 13, 1949, Serial No. 1,951

Term of patent 14 years

(Cl. D14—30)

To all whom it may concern:

Be it known that I, Louis Verderosa, a citizen of the United States, residing at Ozone Park, county of Queens, State of New York, have invented a new, original, and ornamental Design for a Safety Disk Wheel, of which the following is a specification, reference being had to the accompanying drawings, forming a part thereof.

Fig. 1 is a plan view of the convexed face of my safety disk wheel design.

Fig. 2 is a plan view of the dished or concaved face of my safety wheel design.

Fig. 3 is a side elevation view of my invention.

Fig. 4 is a sectional view taken on the lines 4—4 of Fig. 1.

I claim:

The ornamental design for a safety disk wheel, as shown.

LOUIS VERDEROSA.
